Francis D. Hardesty
ATTORNEY

UNITED STATES PATENT OFFICE

HOWARD A. HAYDEN, OF DETROIT, MICHIGAN

CORER

Application filed November 3, 1930. Serial No. 492,928.

This invention relates to corers and more particularly to devices useful in coring certain citrus fruits, especially grapefruit.

An object of the invention is a corer which 5 is operable to core halves of grapefruit, the corer device having a coring ring and a cutter, movable in a plane parallel to the plane of the grapefruit half, and adapted to remove and sever the core formed by the corer 10 ring.

A further object is a simple, easily operable and inexpensive corer and cutter device of the character described above.

Still further objects will readily occur to 15 those skilled in the art upon reference to the following description and the accompanying drawings in which

Fig. 1 is a plan view of the device.

Fig. 2 is a partial sectional view of as if on 20 the line 2—2 of Fig. 1.

Fig. 3 shows a detail of a modification.

As indicated on the drawings, the device includes a corer ring 10 having an annular cutting edge 11. Secured to the ring, as 25 shown, or in any other manner, or even integral therewith, is a cutter (U shaped) and handle member 13, a leg 14 of the member being secured to the ring 10, and a second leg 15 being movable towards and away from the leg 14, the member 13 being made of 30 flexible material, so that the cutter or movable leg 14 does not tend to approach the leg 13 but rather tends to move away from it. The cutter leg 15 carries at its extremity 35 a cutter 16 having a sharpened edge 17, as shown.

In use, the device is grasped in the hand, the member 13 resting in the curled palm and fingers. The corer ring 10 is brought 40 to the exposed plane of the grapefruit half and thrust downwardly, its sharpened edge 11 forming a cylindrical core. The latter is then severed and removed from the grapefruit half by forcing the leg 15 towards the leg 14, the cutter edge 17, severing the core. 45

Fig. 3 shows a device having an auxiliary, vertically disposed blade 21 formed from the leg 14, this form being useful in coring large articles such as melons, whose depth 50 is such that the core must be forced from

the melon body, as well as cut. This form of device when made to the proper size is also useful for coring apples, etc., the cutter 21 being used.

It will be observed that the device is extremely simple of construction and operation, and being of one piece, or of two pieces integrally joined, presents no sanitary or operating difficulties.

It will further be observed that the cutter 60 16 may be disposed on an angle with respect to the axis of the corer to offer less resistance to the insertion of the corer in an object.

Now having described the invention and the preferred embodiment thereof, it is to be 65 understood that the said invention is to be limited, not to the specific details herein set forth, but only by the scope of the claims which follow:

1. A combined corer and cutter including 70 a ring shaped corer and a U shaped element having one leg secured thereto and having a second leg movable therein and towards said first leg, said movable leg carrying a cutter whose cutting plane is transverse to the axis of the ring shaped corer.

2. A combined corer and cutter including 80 a ring shaped corer and a U shaped element having one leg secured thereto and having a second leg movable therein and towards said first leg, said movable leg carrying a cutter whose cutting plane is transverse to the axis of the ring shaped corer, said fixed leg carrying a longitudinally arranged cutter adapted 85 to cooperate with said ring shaped cutter to produce an elongated core.

3. A combined corer and cutter including 90 a ring shaped corer and a U shaped element having one leg secured thereto and having a second leg movable therein and towards said first leg, said movable leg carrying a cutter whose cutting plane is transverse to the axis of the ring shaped corer, said U shaped element being made of strap metal.

4. A combined corer and cutter including 95 a ring shaped corer and a U shaped element having one leg secured thereto and having a second leg movable therein and towards said first leg, said movable leg carrying a cutter whose cutting plane is transverse to the axis 100

of the ring shaped corer, said legs and cutter being integral with one another and with the bight portion of the **U**.

5. A combined corer and cutter including a ring shaped corer and a **U** shaped element having one leg secured thereto and having a second leg movable therein and towards said first leg, said movable leg carrying a cutter whose cutting plane is transverse to the 10 axis of the ring shaped corer, said **U** shaped element being made of strap metal, whereby it is substantially resilient.

6. A combined corer and cutter including a ring shaped corer and a **U** shaped element 15 having one leg secured thereto and having a second leg movable therein and towards said first leg, said movable leg carrying a cutter whose cutting plane is transverse to the axis of the ring shaped corer, said **U** 20 shaped member serving as a handle for the device.

7. A combined corer and cutter including a ring shaped corer and a **U** shaped element having one leg secured thereto and having 25 a second leg movable therein and towards said first leg, movable leg carrying a cutter whose cutting plane is at transverse to the axis of the ring shaped corer, said **U** shaped member being so formed as to project no 30 portions outwardly of said ring shaped corer.

8. A combined corer and cutter including a ring shaped corer and a **U** shaped element having one leg secured thereto and having a 35 second leg movable therein and towards said first leg, said movable leg carrying a cutter whose cutting plane is at transverse to the axis of the ring shaped corer, the dimensions of said cutter being such that it does not project into the core a substantial distance except when it is manually moved towards the fixed leg.

9. A combined corer and cutter including a ring shaped corer and a **U** shaped element 45 having one leg secured thereto and having a second leg movable therein and towards said first leg, said movable leg carrying a cutter whose cutting plane is at transverse to the axis of the ring shaped corer, said movable leg being so flexed as to tend to move away from said fixed leg, whereby it does not interfere with proper coring.

HOWARD A. HAYDEN.
